CLAIM

The ornamental design for a tray, substantially as shown and described.

DESCRIPTION

FIG. 1 is a top perspective view of a tray according to the invention;

FIG. 2 is a left side elevational view of a tray according to the invention

FIG. 3 is a right side elevational view of a tray according to the invention;

FIG. 4 is a front elevational view of a tray according to the invention;

FIG. 5 is a rear elevational view of a tray according to the invention;

FIG. 6 is top plan view of a tray according to the invention; and,

FIG. 7 is a bottom plan view of a tray according to the invention.

The broken, dashed lines shown in the various figures depicting the invention are included for the purpose of illustrating context and do not form any part of the claimed design.
